UNITED STATES PATENT OFFICE.

MICHAEL L. STEGMAIER, OF CUMBERLAND, MARYLAND.

DESIGN FOR A MEAT-MIXING FORK.

54,473.

Specification for Design.

Patented Feb. 10, 1920.

Application filed April 25, 1919. Serial No. 292,746. Term of patent 7 years.

To all whom it may concern:

Be it known that I, MICHAEL L. STEGMAIER, a citizen of the United States of America, residing at Cumberland, in the county of Allegany and State of Maryland, have invented a new, original, and ornamental Design for a Meat-Mixing Fork, of which the following is a specification, reference being had to the accompanying drawing, forming part thereof.

In the drawing:

Figure 1 is a front elevation of a meat mixing fork, showing my design;

Fig. 2 is a side view,

Fig. 3 is a bottom plan view.

I claim:

The ornamental design for a meat mixing fork, as shown.

MICHAEL L. STEGMAIER. [L. S.]
